UNITED STATES PATENT OFFICE.

LEO ABRAM BADGER, OF BURLINGTON, VERMONT, ASSIGNOR OF ONE-HALF TO
ALFRED PERROTTA, OF BURLINGTON, VERMONT.

COMBINED SHUTTLE GUARD AND STOP MOTION.

Application filed May 16, 1927. Serial No. 191,724

My present invention relates to improvements in combined shuttle guard and stop motions for looms of the single thread-warp and single fork type utilizing cams on the auxiliary shaft and as shown in U. S. Patent to Wood, No. 823,248, of June 12, 1906. As is well known in the weaving art the stop-motion includes a filling fork which is arranged on the breast beam in connection with means that control the driving motion of the loom, and the fork is normally retained in such position that it will touch the control means. If however the shuttle passes without leaving a filling thread, or for other well known reasons, the fork having nothing to retain it away from the control means, comes in contact therewith, and immediately stops the operation of the loom. In carrying out my invention I employ in connection with the reed cap of the loom, a spring actuated, normally held, brush bolt, adapted to be projected into position for co-action with the tail of a side fork such as is shown in the said patent of Wood, for the purpose of automatically stopping the loom through the control of the driving mechanism.

The spring actuated brush-bolt is released upon the operation of a push bar or rod extending longitudinally of and suspended 30 from the reed-cap, and means are provided for restoring the bolt or re-setting the stop-motion, as will hereinafter be more fully set forth and claimed.

The initial movement of the raising of the push rod to initiate the stopping of the loom is caused by the shuttle in flight over the float contacting with the push rod and elevating it to cause release of the slide bolt. The slide bolt is then projected by its spring to the position of Figure 2 with its brush in the path of the filling fork that is engaged by connections (including a hook) from the auxiliary cam shaft. The brush holds the fork against movement, and as a result, the hook of the cam connection engages the tail of the fork, thereby stopping the operation of the loom.

In the accompanying drawings I have illustrated one complete example of the physical embodiment of my invention wherein the parts are combined and arranged according to the best mode I have thus far devised for the practical application of the principles of my invention.

Figure 1 is a view in elevation showing 55 sufficient of a loom to illustrate the relation

thereto of the stop-motion of my invention, the latter being in locked or normal position.

Figure 2 is an enlarged, fragmentary view in front elevation showing the bolt sprung, or projected to position for co-action with the filling fork.

Figure 3 is a sectional view at line 3—3 of Figure 2 of the reed and reed-cap, the push bar, and also the detent or pawl for the spring bolt.

Figure 4 is a view from the rear of the reed-cap showing the brush bolt in locked position.

In order that the general arrangement and relation of parts may readily be understood I have indicated in Figure 1 some parts of the loom as the frame D, the harness frame H at the front of which the reed-cap A and reed A' operate in usual manner, and the filling fork in Figures 1 and 2, indicated as F, is designed to be moved forward, of the loom, as the reed-cap swings or oscillates in usual manner, when the parts are set to stop the loom. When the tail of the filling fork is in its depressed position the fork encounters the usual or well known type of hook to stop the driving mechanism of the loom.

The reed-cap carrying the reed A' is of usual type, fashioned of wood, and extends longitudinally of the loom, and operates in well known manner. On the front beveled faces E of the reed-cap or bar A the stop-motion mechanism is carried and actuated or operated through the upward movement, as pressure is applied thereto, of the longitudinally extending push rod 1. This rod is located below the bottom of the reed-cap and in front of the reed, and is provided with upwardly bent ends 2, 2 that are suspended in the vertically arranged brackets 3, 3, spaced apart and attached to the reed cap. Cotter pins 4 are passed through openings in the ends 2 of the rod, and supported on the upper faces of the brackets for the purpose of suspending the push rod in front of and below the reed-cap. The push rod may be moved vertically, or pushed upwardly in its bearing brackets 3 against the tension of a pair of springs 5 that are coiled about these vertical ends and interposed between an anchoring pin 6 passed through the end of the rod and the upper flange of the bracket 3. Thus when the rod is lifted against the tension of the springs, it is returned afterward, to normal position

by the springs.

Intermediate its bent ends the push rod is provided with a number of arms 7 that are rigidly secured to the rod 1 at their lower ends, and at their upper ends are pivoted 5 at 8 to complementary, horizontally disposed, rock arms 9, which arms, in turn, are secured to or rigid with a rock-rod 10 that is journaled in bearings 11 on the beveled face E of the reed-cap. As the upward pressure on the 10 push rod elevates said rod, it will be apparent that this rock-rod will be rocked in its bearings. At one end the rock rod is fashioned with an angularly disposed detent 12 which co-acts with the spring actuated 15 brush-bolt 13 having at one end the tuft or brush 14. The brush-bolt extends longitudinally of the reed-cap and is supported therefrom by means of a bracket 15 secured to the beveled face of the reed cap. At 16 one end of 20 the brush bolt is notched to form a hook, and it will be apparent that this spring actuated brush-bolt is designed to be retained in inoperative position or in normal position, by the engagement of the rock detent 12 with the hook 25 16. To lock or latch the detent and hook, pressure is applied to the push rod to elevate it and thus swing or rock the rock rod 10 and swing the detent outwardly from the reed cap to permit movement to the right in Figure 2 of 30 the brush bolt. As the hook 16 reaches the position for engagement of the detent, pressure is released from the rod 1 and the detent is 35 released from the rod 1 and the detent is swung into the hook, thus holding the brush-bolt. It will readily be seen that when the 40 push rod 1 is again elevated, the detent will be swung outwardly and released from the brush bolt or its hook 16. A spring 17 is coiled about the bolt and located between a fixed washer 18 on the bolt and one of the 45 flanges of the bearing bracket 15, for projecting the brush bolt into position for co-action with the fork F as indicated in Figure 2, and a handle 19 may also be affixed to the slide bolt for sliding it to position for engagement 45 with the detent.

Having thus fully described my invention what I claim as new and desire to secure by Letters Patent is—

1. In a loom the combination of the reed-cap and a side filling-fork, a normally retracted brush-bolt carried by the reed-cap for co-action with the tail of the side filling fork, retaining means for the brush-bolt and means for releasing said retaining means, and means for projecting the released brush-bolt. 55

2. In a combined shuttle guard and stop motion for a loom the combination with a side filling-fork and reed-cap, of a spring pressed, normally retracted brush-bolt carried by the reed-cap, a push-operating means 60 a detent forming part of the push-operating means for retaining the brush-bolt, and means for actuating the push-operating means whereby the brush-bolt is projected to position for co-action with the tail of said side filling fork. 65

3. In a shuttle guard for a loom, the combination with a side filling-fork and the reed-cap, of a spring pressed brush-bolt carried by the cap, a push rod having a spring suspension on said cap, a rock rod and means thereon for retaining the brush-bolt, and actuating means between said push-rod and rock rod whereby the bolt is projected into position for co-action with the tail of the 75 fork. 70

4. The combination in a shuttle guard device with the reed-cap of a brush-bolt and an actuating spring therefor, and a hook on said bolt, of a push-rod and spring suspension therefor on the cap, a rock rod journaled in brackets on the cap and a detent thereon for co-action with said hook, rock arms rigid with said rock rod, and rigid actuating arms on the push rod having pivotal connection 80 with the rock arms. 85

In testimony whereof I hereunto affix my signature.

LEO ABRAM BADGER.
